UNITED STATES PATENT OFFICE.

DANIEL PALMER-JONES, OF LONDON, ENGLAND, ASSIGNOR TO THE TUBULAR SCAFFOLDING COMPANY LIMITED, OF LONDON, ENGLAND.

SCAFFOLDING CLAMP.

Application filed August 4, 1921. Serial No. 469,836.

To all whom it may concern:

Be it known that I, DANIEL PALMER-JONES, a subject of the King of Great Britain, residing at London, England, have invented certain new and useful Improvements in Scaffolding Clamps (an application for British Letters Patent filed February 12, 1918, under No. 2,505, British Patent No. 116,056, dated February 12, 1918), 10 of which the following is a specification.

The present invention refers to a novel construction of clamping apparatus for clamping a first scaffold member to a second scaffold member when the two members are 15 at an angle to each other, and such scaffold members may consist of metal tubes, poles, rods or bars, or they may be composed of wood, but the invention is particularly suitable for connection of such members which 20 are cylindrical and composed of tubular or solid metal.

According to this invention the clamping apparatus comprises two parts, the first part consisting of a U-shaped bracket composed of a plate of metal bent into U-shaped formation, its two parallel wings being each slotted in a direction parallel with the length of the wings, and each wing being 25 formed with inwardly directed hooks adjacent each edge, the U-shaped bracket being adapted to be placed astride a first scaffold member and to receive and hold a second scaffold member in the slots in the wings; a second part comprising a clamping plate is then slidden endwise into the grip of the hooks of the U-shaped bracket, and has a screw threaded hole or holes to 30 receive a pressure screw or screws to act upon the second scaffold member which is 35 in contact with the first scaffold member to secure the two scaffold members together. This clamping apparatus is adapted to be applied to the scaffold members and does not call for the threading of either of the 40 scaffold members through the U-shaped bracket.

The invention will be described with reference to the accompanying drawings, whereon Fig. 1 is a perspective view of the 45 clamping apparatus shown as applied to securing together a vertical and a horizontal tubular scaffold member. Fig. 2 is a sectional side elevation, Fig. 3 is a plan view, and Fig. 4 is a front view of the apparatus 50 applied as shown at Fig. 1.

Referring to the drawings, the first part of the clamping apparatus consists of a U-shaped bracket composed of a plate of metal bent into U-formation, the bend or curve being such that when placed astride a cylindrical vertical scaffold member such as 1, its curved inner surface fits said member, while its side wings 2, 3 extend parallel to each other to a suitable distance beyond said member.

The ends of the two wings 2, 3 of the first part are each formed with inwardly directed hooks 4, 5, and each wing is slotted at 6 centrally in a direction towards the vertical scaffold member embraced by this first 10 part of the clamping apparatus, see Fig. 2.

The second part of the clamping apparatus consists of a plate 7, adapted to be slidden endwise into the grip of the hooks 4, 5 of the first part, so that the plate 7 15 extends in a plane at right angles to the planes of the wings 2, 3 of the first part, and the plate 7 is drilled and screwthreaded and it may be formed with bosses such as 8 around the drill holes, which latter hole or 20 holes receive one or a plurality of pressure screws 9.

In the example now being dealt with two pressure screws are fitted to the plate 7, but obviously the plates might be fitted with 25 only one pressure screw centrally.

With a construction as shown at Figs. 1 to 4, the U-shaped bracket having been placed astride the vertical scaffold member 1, the lateral scaffold member 12 to be secured is 30 then placed in the slots 6 of the wings 2, 3, so that it contacts with the vertical scaffold member 1; then the second part, or plate 7, is slidden into position within the hooks 4, 5, and upon the pressure screw or screws 9 35 being tightened up, their ends will act with pressure on the lateral scaffold member 12, simultaneously forcing the lateral member into pressure contact with the vertical member 1 and causing the plate 7 to act with 40 pressure in the opposite direction against the hooked parts 4, 5 and so bringing the whole of the curved surface of the U-shaped bracket into pressure contact with the vertical member 1 whereby all the parts are 45 firmly and securely held in position.

It is to be observed that with this clamping device the two scaffold members both 50 pass directly through the U-shaped bracket and both scaffold members are simultane- 55 110

ously clamped within the said U-shaped bracket by the pressure screws of the clamping plate. Further the U-shaped bracket is applied to the first scaffold member by a movement of the bracket at right angles to the axis of the first scaffold member while similarly the second scaffold member is placed within the U-shaped bracket by a movement of the second scaffold member in a direction at right angles to the wings of the U-shaped bracket. Therefore in no case is it necessary to slide either of the scaffold members through the U-shaped bracket, and this is an important point because the scaffold members to which this clamping apparatus is particularly applicable are in nearly all cases of considerable length and of such weight that it would be practically impossible to thread the scaffold members through a bracket. It is necessary that the clamping apparatus should be applied to the scaffold members and then the clamping operation effected.

To insure the second part or plate 7 against endway movement, recesses 13 are or may be formed in the face of the plate 7 to receive the hook members 4, 5 of the first part.

As a detail of construction, and when cylindrical lateral members such as 12 Figs. 1 to 4 are to be secured, the pressure bolts 9 may contact with the circular surface of the lateral member 12 slightly below, or slightly above, or in the centre of its section as shown, and it is further desirable that the slots 6 in the side wings of the bracket should extend beyond the periphery of the lateral member 12 in a direction towards the axis of the vertical member 1.

40 What I claim as my invention and desire to secure by Letters Patent is:—

1. In a clamping apparatus for clamping a first scaffold member at an angle to a second scaffold member; the combination of a U-shaped bracket composed of a plate of metal bent into U-shaped formation to be passed onto and embrace a first scaffold member, the two parallel wings of said U-shaped bracket each having a slot extending from its free edge parallel to the length of said wings of said bracket to receive the second scaffold member within said slots of said wings, each wing at its free end having inwardly directed hooks adjacent the edges of said wings, a clamping plate adapted to be slid between and into the grip of said inwardly directed hooks of said U-shaped bracket, and means carried by said clamping plate to act with pressure

upon said second scaffold member within said slots of said U-shaped bracket to clamp said two scaffold members together.

2. In a clamping apparatus for clamping a first scaffold member at an angle to a second scaffold member; the combination of a U-shaped bracket composed of a plate of metal bent into U-shaped formation to be passed onto and embrace a first scaffold member, the two parallel wings of said U-shaped bracket each having a slot extending from its free edge to receive the second scaffold member within said slots of said wings, each wing at its free end having inwardly directed hooks adjacent the edges of said wings, a clamping plate adapted to be slid between and into the grip of said inwardly directed hooks of said U-shaped bracket, said clamping plate having screw threaded holes located to come between the hooked end portions of the wings of said U-shaped bracket when the clamping plate is in position, and pressure screws passing through and engaging said screw threaded holes to act with pressure upon said second scaffold member within said slots of said U-shaped bracket to clamp said two scaffold members together.

3. In a clamping apparatus for clamping a first scaffold member at an angle to a second scaffold member; the combination of a U-shaped bracket composed of a plate of metal bent into U-shaped formation to be passed onto and embrace a first scaffold member, the two parallel wings of said U-shaped bracket each having a slot extending from its free edge parallel to the length of said wings of said bracket to receive the second scaffold member within said slots of said wings, each wing at its free end having inwardly directed hooks adjacent the edges of said wings, a clamping plate adapted to be slid between and into the grip of said inwardly directed hooks of said U-shaped bracket, said clamping plate having recesses in its outer face to receive said inwardly directed hooks of said wings, and means carried by said clamping plate to act with pressure upon said second scaffold member within said slots of said U-shaped bracket to clamp said two scaffold members together.

In witness whereof I have hereunto set my hand in the presence of two witnesses.

DANIEL PALMER-JONES.
